UNITED STATES PATENT OFFICE.

JOHN H. BRINKOP, OF QUINCY, ILLINOIS.

BROOM.

SPECIFICATION forming part of Letters Patent No. 439,470, dated October 28, 1890.

Application filed July 28, 1890. Serial No. 360,125. (No model.)

To all whom it may concern:

Be it known that I, JOHN H. BRINKOP, a citizen of the United States of America, residing at Quincy, in the county of Adams and 5 State of Illinois, have invented certain new and useful Improvements in Brooms, of which the following is a specification.

It is the object of my invention to provide a broom with means whereby it may be hung 10 up when not in use, the invention being applicable to house-brooms, whisk-brooms, and the like.

In carrying out my invention I combine with the body of the broom an eye or ferrule 15 passing through the same between the straws from side to side, so that when not in use it may be hung up by this means, the nail or supporting-peg extending through the opening in the eye or ferrule.

20 In the accompanying drawings, Figure 1 is a front view of the broom, and Fig. 2 a central section of the same.

In the drawings the broom is of ordinary construction, having the usual binding-cords 25 1 2. The eye or ferrule A is preferably made of metal, and it is inserted through the broom

up near the head, the straws and broom-corn being spread apart to admit it.

The ferrule is constructed of two sections 3 4, each of which has a flange 5, and in placing the eye or ferrule through the broom one section fits tightly within the other, and the two sections are forced together until the flanges bear closely upon the sides of the broom. The ferrule is preferably located be- 35 tween the binding-cords 1 2, and the straws being held by the same against undue spreading exert a pressure against the ferrule, and thus retain it in place.

I claim as my invention—

In combination with a broom, an eye or fer- 40 rule extending through the same between the straws and the binding-cords, one above and the other below the ferrule, whereby the straws are firmly held about the ferrule to 45 retain the same, substantially as described.

In testimony whereof I affix my signature in presence of two witnesses.

JOHN H. BRINKOP.
